HAT PEG OR THE LIKE

Arnold Noble, Halifax, and Thomas Phenix
Walkland, Morecambe, EnglandApplication March 29, 1935, Serial No. 13,746
In Great Britain April 5, 1934

2 Claims. (Cl. 211—32)

The invention relates to hat pegs and like supporting devices suitable for attachment to seat backs in cinemas, theatres and similar places, to pin rails and in other positions for private or public use, of the kind comprising a separate weighted peg member slidably mounted in a socket or container and collapsible therein so as to avoid projection therefrom when not in use.

10 The object of the present invention is to provide a more simple and improved construction of hat peg device of the kind aforesaid.

According to the invention, the improved device comprises two elements, a socket or container, and a peg element normally occupying a collapsed position within the socket and being provided at its lower end with a rounded enlargement integral with the peg or fixed rigidly thereto and serving as a weight for facilitating the return of said peg to the socket on the removal of its load. Additional means may be provided for assisting in said return. Pegs of this construction not only facilitate the return of the peg to the socket when relieved of its load, but they are capable of lateral arcuate movements when functioning as a support for umbrellas, handbags or the like.

When the device is not in use, a portion of said peg projects through an aperture in the top 30 of the socket and the peg is raised thereby and moved into an angular position suitable for supporting an article thereon; the leverage and the weight of said article are adapted to set up friction between the peg and the aforesaid aperture, sufficient to maintain the peg in its raised position. The removal of the article from said peg causes the enlargement at the lower end thereof to return the peg to its normal position within the container. Means may be provided 40 within the container for eliminating shock and noise consequent on said return. Furthermore, the appliance, if desired may have associated therewith pockets for tobacco ashes, spent matches or the like, when required for attachment to seats.

The invention will now be described with reference to the accompanying sheet of drawings, in which:—

Figure 1 is a front elevation of a hat or like peg constructed according to the present invention, showing the peg occupying its normal position within the container when not in use.

Figure 2 is a plan view of Figure 1.

Figure 3 is a sectional side elevation of Figure 1.

Figure 4 is a sectional side elevation of Figure 1, secured to a fragmentary part of a seat back, showing the peg in its raised position for supporting a suitable article.

Figures 5 and 6 are a sectional plan and a front elevation of a modification of Figure 1, through the lines VI—VI and V—V, respectively.

Figure 7 is a sectional side elevation of a further modification of Figure 1 showing additional means for facilitating the return of the peg 10 within the casing, also in broken lines the normal position of said peg on the removal of the article previously supported thereby.

Figure 8 is a front elevation of an additional modification of Figure 1, showing ashes pockets 15 associated therewith.

Similar letters refer to similar parts throughout the several views.

Referring to Figures 1, 2, 3 and 4 of the drawing: The hat peg is a loose element A of a suitable length provided at the lower end with an enlarged knob or the like B, the outer or opposite end being plain or provided with a terminal ornamentation C.

The peg A is housed within a suitable hollow vessel or container D provided with flanges or projections E, E, by which the appliance is attached by screws to the seat back, pin rail or the like F.

For convenience in manufacture and in the housing of the peg within the container, the container is provided with a bore or chamber G adapted to permit freedom to said peg in its movements therein when container D is secured in position, as clearly shown in Figures 3 and 4 of the drawing. The said container is also open at the back and is provided with an aperture in the form of a slot H with rounded ends in the top J thereof, through which projects for a suitable distance, the peg with a terminal ornament C thereon. The enlargement B is of a size adapted to prevent said peg from passing through said aperture H, it also serves as a weight for returning the peg to the normal position shown in Figure 3, on removal of the article 45 therefrom, and is more or less round in cross-section which enables the peg when raised into position for supporting an article, to move arcuately in a lateral direction when engaged by the dress or person of a passer-by.

In a modification, more particularly adapted for supporting coats and similar articles of wearing apparel (see Figures 5 and 6 of the drawing), grooves K may be formed in the vertical sides of the container D adapted to receive trun- 50 55

nions L formed on the part B for the purpose of guiding and facilitating the return of the peg to its normal position on removal of the article being supported.

5 In a further modification applicable to larger sizes of this device (see Figure 7 of the drawing), a spring M may be fitted on the peg in abutment upon the part B, which is compressed on the raising of the peg A into position for 10 supporting an article, expanding on the removal of the article therefrom and assisting the return of the peg to the position shown in broken lines.

15 Referring to Figure 8 of the drawing: N are pockets embodied in the appliance, adapted to receive tobacco ashes, spent matches or the like.

P is a rubber or like cushion in the bottom of the chamber G for eliminating the noise of impact on the return thereto of the peg.

20 When in use the appliance is secured to the seat back P or the like in a vertical position, as clearly shown in Figures 4 and 7 of the drawing, and when it is desired to use the peg it is raised until the part B engages the top J, the 25 peg is then moved into an angular position as clearly shown in Figures 4 and 7, to receive the article to be carried, the weight of the article, the leverage and the frictional contact of the peg A in engagement with the sides of the aperture H, contributing to maintain said peg in the raised position for the purposes before mentioned.

30 On removing the article from the peg, the peg is automatically released and by reason of the angle occupied, the heavy end, or the spring abutting thereon, the peg immediately drops back into the container.

What we claim as our invention and desire to secure by Letters Patent, is:—

1. An article holding device adapted to be secured to a seat back, pin rail or the like, comprising a holder provided with an open back and a slotted aperture in its top, and a peg normally housed within said holder, provided with a spheroidal enlargement at its lower end, said peg being adapted when in active use to slide within said slot whereby the peg is capable of 10 both a vertical and a lateral arcuate movement and when relieved of its load to automatically return to the holder.

2. A two piece article holder of the class described including a casing arranged to be connected to a support, said casing having an opening in its top, a rigid elongated peg arranged to be housed within the casing, said peg having its upper end portion extending through said opening and provided with an enlargement 20 at its lower end arranged to engage the bottom of the casing when in its inoperative position and adapted to engage the wall of the opening for limiting the upward and outward movement of the peg, said peg being capable of both a 25 vertical and lateral arcuate movement and when in its operative position, being bodily inclined relative to the casing and retained in this position by engagement of the enlargement with the wall of said opening so that upon being relieved 30 of the weight of the article thereon to automatically return to its inoperative position within the casing.

ARNOLD NOBLE.

THOMAS PHENIX WALKLAND.
